US00D871368S

(12) **United States Design Patent** (10) **Patent No.:** **US D871,368 S**
Saule et al. (45) **Date of Patent:** **** Dec. 31, 2019**

(54) **HEADPHONES**(71) Applicant: **Dolby Laboratories Licensing Corporation**, San Francisco, CA (US)(72) Inventors: **Lucas E. Saule**, San Francisco, CA (US); **Vincent Voron**, Menlo Park, CA (US); **Peter Michaelian**, San Francisco, CA (US); **Guangyu Jin**, San Francisco, CA (US); **Kevin J. Kilpatrick**, Mountain View, CA (US); **Branko Lukic**, Menlo Park, CA (US); **Steven Ryutaro Takayama**, Menlo Park, CA (US); **Grayson H. Byrd**, San Francisco, CA (US); **Adam Scott Koniak**, Redwood City, CA (US); **Ariel Laurent Fischer**, San Francisco, CA (US); **Robert Edward Borchers**, Pleasanton, CA (US)(73) Assignee: **Dolby Laboratories Licensing Corporation**, San Francisco, CA (US)(**) Term: **15 Years**(21) Appl. No.: **29/662,004**(22) Filed: **Aug. 31, 2018**(51) LOC (12) Cl. **14-01**

(57)

CLAIM

The ornamental design for headphones, as shown and described.

DESCRIPTION

FIG. 1 is a perspective view of headphones showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.

The dot-dash broken lines illustrate boundaries which form no part of the claimed design.

1 Claim, 6 Drawing Sheets# US D871,368 S
